(No Model.)

A. VON BRANDIS.
PERFORATING STAMP.

No. 447,089.

Patented Feb. 24, 1891.

UNITED STATES PATENT OFFICE.

ADOLPH VON BRANDIS, OF MILWAUKEE, WISCONSIN.

PERFORATING-STAMP.

SPECIFICATION forming part of Letters Patent No. 447,089, dated February 24, 1891.

Application filed June 21, 1890. Serial No. 356,180. (No model.)

To all whom it may concern:

Be it known that I, ADOLPH VON BRANDIS, of Milwaukee, in the county of Milwaukee, and in the State of Wisconsin, have invented 5 certain new and useful Improvements in Perforating-Stamps; and I do hereby declare that the following is a full, clear, and exact description thereof.

My invention relates to perforating-stamps; 10 and it consists in certain peculiarities of construction and combination of parts whereby various groups of arbitrarily-selected characters may be accurately determined and indefinitely reproduced in perforations on bank- 15 checks, bonds, &c., with absolute certainty, all the characters in each group being reproduced by a single operation, as will be herein-after described with reference to the accompanying drawings, and subsequently claimed. 20 In the drawings, Figure 1 represents a side elevation of my improved perforating-stamp partly broken away; Fig. 2, a sectional view of the same on line 2 2 of the preceding figure; Fig. 3, a detail plan view, partly in horizontal section on line 3 3 of Fig. 2 and partly broken away; Fig. 4, a detail horizontal section on line 4 4 of Fig. 1, and Fig. 5 a diagram on line 5 5, Fig. 2.

Referring by letter to the drawings, A represents the base of my device, provided with slotted standards B, the latter serving as guides for sliding blocks C, having squared openings for correspondingly-shaped portions b of a shaft D, that forms the bearing for a 35 series of rotary adjustable polygonal die-plates E, the faces of the die-plates being provided with pins c, arranged to form arbitrarily-selected characters. Each die-plate is provided with a series of apertures d, that 40 correspond in number to the faces of said die-plate, and each sliding block has an aperture that corresponds in diameter to those in the die-plates. The die-plates being rotary adjustable, they are locked in their adjusted position by means of a rod F, passed 45 through those apertures in said die-plates that register with the apertures in the sliding blocks C, and I prefer to provide the rod with a transverse groove e for engagement with a latch f, pivoted to one of the standards B of the device. This engagement of the groove

and latch prevents accidental displacement of the rod F, and by having the latter of sufficient length, as shown in Fig. 2, it may be used as a means for actuating the stamp 55 formed by the several die-plates, the latter and the sliding blocks C being returned to and held in their normal position by means of springs G, connecting arms g of the shaft D with the ends of a cross-brace H, that unites 60 the upper ends of the standards B, as best illustrated in Fig. 1. While the rod F may serve the purpose just described, I find it convenient to trunniion a L-shaped lever I in the upper ends of the standards B and connect lateral arms h of this lever with the ends of the shaft D by means of irregular links J, the shape of these links being such as not to interfere with said rod in case the latter is projected in the path of said links. 70

Supported on the base A is a bed-plate K, provided with rows of vertical perforations i, parallel to each other in longitudinal and transverse directions, and a recess j in the bed-plate forms a space between said base 75 and perforations for the reception of the punched-out material. Hinged to the bed-plate K is a frisket comprising a frame L and thin bottom piece M, the latter being provided with parallel rows of perforations k, designed 80 to register with those in said bed-plate. Springs N are preferably connected to the standards B of the device to impinge against the frisket, and thereby clamp the latter firmly against the material on the bed-plate 85 in position to be perforated. In practice it will be found of advantage to roughen the opposing faces of the bed-plate and frisket, in order to secure a better hold on the material to be perforated. In Fig. 1 the frisket is 90 shown in its raised position; but the normal position of said frisket is shown in Figs. 2 and 3.

Adjacent to the pins c on the die-plates I prefer to paint or otherwise display arbitrary 95 index-characters, as shown in Fig. 2, and I also prefer to have the same characters above and below said pins, this being a matter of convenience in the reading of said characters. The characters displayed at any time on those 100 faces of the several die-plates that come nearest to and immediately in front of the oper-

ator coincide with the characters formed by the pins on those faces of said die-plates immediately above the perforating-point. Consequently it is obvious that the operator can 5 readily arrange any desired group of pin characters by shifting the die-plates until the desired group in register with the perforating-point is indicated by corresponding painted characters in plain sight. This being done, 10 the die-plates and sliding blocks C are locked together by the rod F; and thus the press is set for perforating the group of arbitrarily-selected characters.

A number of the characters on the die- 15 plate at the left of the operator are preferably representations of values—as, for instance, the letter "F" stands for "francs;" but all the characters on said die-plate may be such as fancy or the requirements of a particular 20 business may dictate. Each of the other die-plates have characters representing the figures 1 to 0, inclusive, and these latter die-plates may have such other characters or designs as may be found desirable.

25 As shown in Fig. 2, the characters displayed on opposite sides of the pins on the faces of die-plates nearest to and immediately in front of the operator read F 0 5 6 + 1, and consequently the pin characters over the perforating-point are in the same arrangement as shown by the diagram, Fig. 5. The group of characters having been once arranged, the perforating of the same group may be repeated indefinitely with absolute certainty 30 without any rearrangement of the die-plates, and the latter cannot be shifted either intentionally or otherwise until the locking-rod is withdrawn.

Attention is called to the fact that by having the perforations in the frisket and bed-plate arranged in rows parallel to each other in longitudinal and transverse directions I do away with the necessity of having to arrange a separate set of perforations for each 45 character formed by the die-plate pins.

Having thus described my invention, what I claim as new, and desire to secure by Letters Patent, is—

1. A perforating-stamp comprising a frame, 50 a shaft reciprocative therein, a series of plates rotarily adjustable on the shaft and provided at intervals with pins arranged to form arbitrary characters, suitable means for locking the plates in their adjusted position, and a bed-plate provided with rows of perforations 55 parallel in longitudinal and transverse directions, substantially as described.

2. A perforating-stamp comprising a frame, a shaft reciprocative therein, a series of plates 60 rotarily adjustable on the shaft and provided at intervals with pins arranged to form arbitrary characters, suitable means for locking the plates in their adjusted position, a bed-plate provided with rows of perforations 65 parallel in longitudinal and transverse directions, and a frisket hinged to the bed-plate and also provided with perforations corre-

sponding to those in the bed-plate, substantially as described.

3. A perforating-stamp comprising a frame, 70 a shaft reciprocative therein, a series of plates rotarily adjustable on the shaft and provided at intervals with pins arranged to form arbitrary characters, suitable means for locking the plates in their adjusted position, a bed-plate provided with rows of perforations 75 parallel in longitudinal and transverse directions, a perforated frisket hinged to the bed-plate and also provided with perforations corresponding to those in said bed-plate, and springs arranged to impinge against the frisket, substantially as described.

4. A perforating-stamp comprising a frame, apertured blocks reciprocative therein, a shaft fitted to the blocks, a series of apertured 85 plates rotarily adjustable on the shaft and provided at intervals with pins arranged to form arbitrary characters, a rod for insertion in registering apertures of the blocks and plates, and a bed-plate provided with 90 rows of perforations parallel in longitudinal and transverse directions, substantially as described.

5. A perforating-stamp comprising a frame, apertured blocks reciprocative therein, a shaft fitted to the blocks, a series of apertured 95 plates rotarily adjustable on the shaft and provided at intervals with pins arranged to form arbitrary characters, a rod for insertion in registering apertures of the blocks and plates, 100 a latch on the frame for engagement with the rod, and a perforated support for the material to be operated upon, substantially as described.

6. A perforating-stamp comprising a frame, 105 apertured sliding blocks arranged therein, a shaft fitted to the blocks, a series of apertured plates rotarily adjustable on the shaft and provided at intervals with pins arranged to form arbitrary characters, a rod for insertion in 110 registering apertures of the blocks and plates, a latch on the frame for engagement with the rod, a lever trunnioned to said frame and linked to said shaft, and a perforated support for the material to be operated upon, 115 substantially as described.

7. A perforating-stamp comprising a base provided with slotted standards, blocks reciprocative in the standard-slots, a spring-controlled shaft fitted to the blocks, a series of apertured plates rotarily adjustable on the 120 shaft and provided at intervals with pins arranged to form arbitrary characters, a rod for insertion in the registering apertures of said blocks and plates, a latch on the frame for engagement with the rod, a perforated bed-plate supported on the frame-base, and a perforated frisket hinged to the bed-plate, 125 substantially as described.

8. A perforating-stamp comprising a base 130 provided with the slotted standards B, the blocks C, loosely arranged in the standard-slots, a shaft fitted in the blocks and provided with arms g, the brace H, uniting said stand-

ards at their upper ends, the springs G, connecting the shaft-arms and said brace, plates rotarily adjustable on the shaft and provided at intervals with pins arranged to form arbitrary characters, a perforated support for the material to be operated upon, and a lever mechanism for reciprocating said blocks, substantially as set forth.

In testimony that I claim the foregoing I have hereunto set my hand, at Milwaukee, in the county of Milwaukee and State of Wisconsin, in the presence of two witnesses.

ADOLPH VON BRANDIS.
